UNITED STATES PATENT OFFICE.

GEORGE WASHINGTON HODESTY, OF DRIFTON, PENNSYLVANIA.

COAL-SCUTTLE.

SPECIFICATION forming part of Letters Patent No. 317,786, dated May 12, 1885.

Application filed March 20, 1885. (No model.)

To all whom it may concern:

Be it known that I, GEORGE W. HODESTY, a citizen of the United States, residing at Drifton, in the county of Luzerne and State of Pennsylvania, have invented a new and useful Improvement in Coal-Scuttles, of which the following is a specification, reference being had to the accompanying drawings.

My invention relates to coal-scuttles, and more particularly to that class in which a reservoir or compartment is provided to catch the drippings from the coal, and it has for its object to improve and simplify articles of this class.

With these ends in view the invention consists in the combination, with a coal-scuttle, of a compartment or reservoir and a hinged bottom having a series of holes or openings.

The invention further consists in the improved construction and combinations of parts, hereinafter fully described, and pointed out in the claims.

In the drawings, Figure 1 is a plan view of a coal-scuttle embodying my invention. Fig. 2 is a longitudinal vertical section of the same. Fig. 3 is a plan view of a modification, and Fig. 4 a vertical section of the same.

In the accompanying drawings, in which like letters of reference indicate corresponding parts in all the figures, A represents the scuttle, which is of the ordinary well-known construction, and is provided with a pivoted bail or handle, B.

C represents the mouth of the scuttle, and D the inclined front end of the same.

E represents a metal strip or plate, which is secured to the inner sides of the scuttle at the inclined front end of the same, so as to form a space or chamber, a. The upper end of the strip or plate E is bent outwardly and secured to the mouth of the scuttle, thus closing the upper end of said space or chamber. The lower end of the metal strip or plate terminates at a point a short distance from the bottom of the scuttle, and hinged to the lower end of the plate E is a supplemental bottom, F, which is formed with a series of holes or openings, b. The said supplemental bottom is provided with downwardly-extending flanges, as set forth. 50 c, which rest or bear upon the bottom of the

scuttle, and serve to form a space between the bottom and supplemental bottom.

The operation is as follows: When coal is placed in the scuttle, if there be any water in the same it will pass through the coal into the space between the supplemental bottom and the bottom through the holes or openings b, and when the scuttle is tilted the water will run into the space or chamber a, and is thus prevented from entering the stove with the coal. Should the space below the supplemental bottom become filled with siftings or fine particles from the coal, the said bottom may be easily raised and the siftings removed.

In the modification shown in Figs. 3 and 4 the plate E is provided with a series of vertical slots adjacent to its lower end, and the supplemental bottom is provided with slots instead of perforations or openings.

Having fully described my invention, what I claim as new, and desire to secure by Letters Patent, is—

1. The combination, with a coal-scuttle, of a vertically-arranged plate forming a vertical chamber, and a hinged supplemental bottom. 75

2. The combination, with a coal-scuttle, of a strip, E, forming a chamber at the front end of the scuttle, and a supplemental bottom hinged to the lower end thereof and having a series of openings. 80

3. The combination, with a coal-scuttle, of a plate, E, bent at its upper end and secured to the upper front end of the scuttle, and secured to the inner sides so as to form a chamber open at its lower end, and a supplemental bottom hinged to the lower end of said plate and supported on a horizontal line therewith, said bottom having a series of openings. 85

4. The combination, with a coal-scuttle, of a plate, E, secured to the inner side and forming a chamber, and a hinged bottom having a series of holes or openings and downwardly-extending flanges, as set forth. 90

In testimony that I claim the foregoing as my own I have hereto affixed my signature in presence of two witnesses.

GEORGE WASHINGTON HODESTY.

Witnesses:

JOHN WHAREN,

ELLIOTT A. OBERRENDER.

Corrections in Letters Patent No. 317,786.

It is hereby certified that in Letters Patent No. 317,786, granted May 12, 1885, for an improvement in "Coal-Scuttles" the name of the patentee was erroneously written and printed "George Washington Hodesty," whereas it should have been *George Washington Hadesty*; that the proper corrections have been made in the files and records pertaining to the case in the Patent Office, and should be read in the Letters Patent to make the same conform thereto.

Signed, countersigned, and sealed this 16th day of June, A. D. 1885.

[SEAL.]

H. L. MULDROW,
Acting Secretary of the Interior.

Countersigned:

M. V. MONTGOMERY,
Commissioner of Patents.
